T. INOUYE.

YARN AND THREAD HOLDER FOR CROCHETERS AND KNITTERS.

APPLICATION FILED MAR. 8, 1915.

1,219,399.

Patented Mar. 13, 1917.

UNITED STATES PATENT OFFICE.

TOKUGERO INOUE, OF LOS ANGELES, CALIFORNIA.

YARN AND THREAD HOLDER FOR CROCHETERS AND KNITTERS.

1,219,399.

Specification of Letters Patent. Patented Mar. 13, 1917.

Application filed March 8, 1915. Serial No. 13,039.

To all whom it may concern:

Be it known that I, TOKUGERO INOUE, a subject of the Mikado of Japan, residing at Los Angeles, in the county of Los Angeles 5 and State of California, have invented a new and useful Yarn and Thread Holder for Crocheters and Knitters, of which the following is a specification.

This invention relates to the class of yarn 10 and thread holders adapted for detachable attachment to the arm of the user.

An object of the invention is to provide a device of this character of simple, light, neat character into which one or more spools 15 or balls of yarn or thread may be applied and from which the strand or strands will be delivered to the hand of the knitter or crocheter in a convenient and satisfactory manner, and in order to do this I have made 20 provision whereby the axis of the spool or ball can be adjusted relative to the axis of the clamp that connects the device with the arm of the user, and I also provide a guide in connection therewith.

25 Objects of the invention are, increased convenience for use, increased security for connecting the spool of yarn or thread to the arm of the user; and provision for directing a plurality of strands from the holder; also 30 to adjust the tension on the spool or ball.

Further objects are cheapness, economy of material, and simplicity and ease of constructing and assembling the parts.

The invention may be carried out in various 35 ways and includes a form adapted for holding a plurality of spools and also a form adapted for holding only one spool.

The holder may be made mainly of stamped and pressed sheet material and the 40 spool carrying device may be made adjustable by either slip or screw joints and telescoping parts.

The accompanying drawings illustrate the 45 invention.

Figure 1 is a perspective view of a form of the invention in which provision is made for holding two spools and directing two strands therefrom.

Fig. 2 is a fragmental section taken 50 through one of the spools on line x^2-x^2 , Figs. 1 and 3, showing a slip form of spool adjustment.

Fig. 3 is a fragmental vertical mid-section taken on line x^3-x^3 , Fig. 2.

55 Fig. 4 is a perspective view of the holder

as constructed for holding a single spool and guiding a single strand therefrom.

Fig. 5 is a spool section analogous to Fig. 2 showing a screw form of spool adjustment.

In the embodiment shown two U-shaped 60 members 1, 2 are mounted in reverse relation to each other, the member 1 being adapted to slip onto a support such as the arm of the knitter and the member 2 serving to carry one or more balls 3 of yarn.

65 Said U-shaped members may be arranged back to back with their bends juxtaposed as in Fig. 4, to carry one ball of yarn, or the member 2 may comprise two or more U-supports as at 4, 5 carried upon a cross-piece 70 6 that is mounted upon the member 2 as in Fig. 1, the number of U-supports varying according to the number of balls it is desired to support.

75 Referring now to Figs. 1, 2 and 3 the members 1 and 2 are held in swiveled relation to one another by means of central perforations 7 and 8 in the member 1 and cross-piece 6 respectively, through which perforations a stud 9 extends. A thumb 80 nut 10 screws upon the threaded end of the stud and serves to clamp said members together.

A standard 11 soldered at 12 or otherwise secured to the cross-piece 6, extends 85 upwardly intermediate the supports, 4, 5, to serve as a thread guide and terminates in eyes 13 and 14 through which the unwound strands 15 and 16 are passed from the balls 3. The soldered lower portion of 90 said standard 11 may extend under the nut 10 that clamps the members 1 and 2 together, as shown in Fig. 3, to more firmly secure the standard in place. The free part 95 of the standard is preferably straight and parallel with the sectional planes drawn longitudinally through the middle of the U-shaped members.

The U-supports 4, 5 are each provided 100 with spool bearings 17 which are shown preferably adjustable, said bearings supporting a spool 18 formed of side flanges 19 and hollow tubular members 20 extending therefrom, the tubular members telescoping one within the other as the flanges 105 are brought tight against the ends of the yarn ball. This relative movement of the flanges 19 permits adjustment of the spool bearing for various sizes of balls or spools.

110 To secure a tight slip joint between the

telescopic members the inner one may be axially slotted as at *s* and the slit edges slightly pressed together upon inserting into the outer telescopic member thus to provide a slight spring tension between said inner and outer members.

The bearings 17 are adjustable to accommodate the different lengths of spools and to avoid looseness in the case of shorter spools. To this end the terminals of the **U**-supports 4, 5 are provided with inwardly projecting tubular pins which form the bearings, and sleeves 21 flanged as at *a*, are provided for the pins; said pins being also axially slotted as at *s'* to afford the sleeves a tight sliding fit over the pins so that when the spool is in place a sleeve may be moved along its pin and inserted into the axial hole of the spool to frictionally hold the spool or may be retracted therefrom to release the spool. The supporting members 4, 5 are resilient, and therefore the arms of each may be spread apart to facilitate the entrance of the spools to position for use.

The pins and sleeves may be threaded as in Fig. 5 if desired so that adjustment in this case is made by turning a sleeve back and forth upon its pin.

30 The two members 1, 2 are swiveled together and may be freely revolved relative to each other when the thumb nut 10 is loosened, thus to allow the spools and standard 11 to face in any desired direction 35 while the member or clip 1 is clamped upon the arm of the user. It is seen that when the standard is in the central relation to the axes of the spools shown in Figs. 1 and 4 the thread will thereby be guided so 40 that it cannot slip off at the ends of the spools and thus become entangled.

In the form shown in Fig. 4 a single spool 18' is mounted directly between the bearings 17 at the ends of the member 2 and the 45 thread guide 11 is preferably formed with a laterally projecting arm *b* and an upright arm *c*, said arm *c* terminating in a single eye 22 through which the unwound strand 23 is passed from the single ball 3. The 50 thread guide is loosely mounted in this case being swiveled on the stud 9 that passes directly through the backs of the members 1, 2 and arm *b*. By this arrangement the guide may be swung as desired relative to 55 the bearing whenever the nut 10 is loosened, to thereby direct the thread or yarn as required and then the nut will be tightened to clamp the members and guide in fixed relation to each other.

60 In practical use different knitters and crocheters find it desirable to lead the thread or yarn from the holder in various ways and directions relative to the position of the arm to which the arm clip member 1 is applied, 65 and by this present invention the change

from the direction of the axis of the bearings relative to the arm-receiving space between the limbs of the lower clip member 1 is readily made while in the single form the guide may be readily shifted from center to side of the spool as may be desired. 70

The tension is adjusted by tightening the sleeve 21.

I claim:

1. Two **U**-shaped members mounted back to back so that they open in reverse relation to each other; a standard; and means to swivel and clamp the members and standard together; one of the members being provided with laterally adjustable means adapted to hold a spool; the free part of said standard being straight and parallel with the sectional planes drawn longitudinally through the middle of said members and being provided with means to guide a thread or yarn from said spool; and the guide and one of said members being relatively adjustable. 75 80 85

2. The combination with a lower **U**-shaped member for attachment to the arm of a person; of an upper **U**-shaped member arranged to open reversely to said lower member, said upper member being provided with laterally adjustable means adapted to support a spool; a standard mounted on said upper member; the outer part of said standard being straight and parallel with the sectional planes drawn longitudinally through the middle of said members and being provided with means to guide a thread or yarn from said spool; and the upper and lower members being relatively adjustable. 90 95 100

3. The combination with a lower **U**-shaped member for attachment to the arm of a person; of an upper **U**-shaped member arranged to open reversely to said lower member; said upper member being provided with laterally adjustable bearings adapted to support a spool; a standard mounted on said upper member; the outer part of said standard being straight and parallel with the sectional planes drawn longitudinally through the middle of said members and being provided with means to guide a thread or yarn from said spool; and the upper and lower members being relatively adjustable. 105 110 115

4. The combination with a lower **U**-shaped member for attachment to the arm of a person, of a cross-piece mounted upon the back of said member, a plurality of upper **U**-shaped members carried by said cross-piece and arranged reversely to said lower **U**-shaped member, said upper members being provided with bearings to support a plurality of spools, and means on the cross-piece and extending up intermediate the upper members to guide the thread or yarn from said spools. 120 125

5. The combination with a centrally 130

perforated lower U-shaped clip, of a centrally perforated cross-piece mounted on the back of said clip, a stud extending through the perforations, a thumb nut on 5 the stud to adjustably clamp the lower clip and cross-piece together, upper U-shaped clips carried by said cross-piece and arranged reversely to said lower clip, adjustable means to mount a spool between the 10 ends of said upper U-shaped clips, the lower U-shaped clip being adapted for detachable attachment to the arm of the knitter, and the cross-piece and lower clip being swiveled on said stud when the nut is loosened 15 and held in fixed relation to each other when the nut is tightened.

6. A spool holder comprising two resilient U-shaped members arranged to open reversely to each other, one of said members 20 having laterally adjustable terminal bearings; a standard having an eye in its outer part and being spaced apart from said bearings; said outer part being straight and parallel with the sectional planes 25 drawn longitudinally through the middle of said members; and adjustable means to

swivel and clamp said members and standard together so that the thread guide arm may be adjusted relative to the other two members of the spool holder. 30

7. Two U-shaped members mounted back to back so that they open in reverse relation to each other; a standard; and means to swivel and clamp the members and standard together; one of the members being 35 provided with laterally adjustable means adapted to hold a spool; the outer part of said standard being straight and parallel with the sectional planes drawn longitudinally through the middle of said members 40 and being provided with means to guide a thread or yarn from said spool; and the guide and both of said members being relatively adjustable.

In testimony whereof, I have hereunto 45 set my hand at Los Angeles, California, this 27th day of February, 1915.

TOKUGERO INOUYE.
